UNITED STATES PATENT OFFICE.

RODNEY G. RICHARDSON, OF CHICAGO, ILLINOIS, ASSIGNOR TO AUTOMATIC ELECTRIC INC., OF CHICAGO, ILLINOIS, A CORPORATION OF DELAWARE.

TRUNKING ARRANGEMENT FOR AUTOMATIC TELEPHONE SYSTEMS.

Original application filed October 11, 1921, Serial No. 507,009. Divided and this application filed June 10, 1925. Serial No. 36,117.

This application is a division of application #507,009, filed October 11, 1921, patented October 6, 1925, #1,556,307.

The present invention relates to trunking arrangements for automatic telephone systems in general, but is concerned more particularly with trunking arrangements for such systems as employ non-numerical trunk selecting switches that are seized by automatic selector switches; and the principal object, briefly stated, is the provision of new and improved trunking arrangements whereby the trunk selecting movement of a non-numerical switch in a system of this type, or the maximum number of trunks which such a switch will have to test to find an idle one, is considerably reduced.

Another object is to provide an improved non-numerical switch using a plurality of relays to select an idle trunk instead of the usual step by step movement.

Still another object is to provide improved circuits for rendering all the trunks incoming to a particular secondary group busy while the trunks outgoing from that group are all in use.

A still further object is the provision of new and improved circuit arrangements whereby the operation of a selector switch is improved.

These objects, together with others that are not specifically pointed out now, will be more fully pointed out hereinafter, reference being had to the accompanying drawings comprising Figures 1-5, inclusive, which show by means of the usual circuit diagrams sufficient of the apparatus employed in a system embodying the principles of the invention to enable the same to be understood.

In the drawings, Figs. 1 and 2, when placed together with Fig. 1 over Fig. 2 and with the corresponding lines at the ends of the sheets in alignment, represent a trunking layout in which a major group of thirty trunks shown on the right hand side of the two sheets is accessible through non-numerical switches to the major group of fifty trunks shown on the left hand side of the two sheets.

Figs. 3 and 4, when arranged in order with the corresponding lines in alignment, represent sufficient of the apparatus used in the trunking layout shown in Figs. 1 and 2 to enable the same to be understood.

Fig. 5 is a circuit diagram showing a group of non-numerical switches which are different from those shown in Fig. 3. These switches are of a type which may also be used in a layout such as is shown in Figs. 1 and 2, and for convenience it will be assumed that the system includes both types of switches.

Referring now particularly to Figs. 1 and 2, the trunking layout shown therein will be explained more in detail. It has heretofore been the practice, when the so called plunger type of non-numerical switches are used in similar layouts, to divide the major group of outgoing trunks, or the group which corresponds to the group shown on the right hand side of the two drawings, into sub-groups of ten trunks each, in accordance with the number of trunks to which a plunger type switch has access. Similarly, when step by step rotary non-numerical switches are used the practice has been to divide the major group of outgoing trunks into sub-groups of twenty-five trunks each, in accordance with the number of trunks to which a switch of this type has access. This practice, so far as is known, has been followed invariably, regardless of the number of trunks in the major group. In the present case, however, the major group of outgoing trunks is preferably divided into ten sub-groups, corresponding to the number of trunks to which a selector switch has access in any one level. As shown, there are thirty outgoing trunks in the major group and consequently there are three outgoing trunks in each sub-group. If the major group comprised forty outgoing trunks then each sub-group would comprise four trunks, or if the major group comprised only twenty trunks then each sub-group would comprise only two trunks. It will be seen now that as long as the major group of outgoing trunks is less than 100 there will not be as many as ten trunks per sub-group, which heretofore has been the minimum number, and with major groups of a number much less than 100 the number of trunks in each sub group is correspondingly less and consequently the switches which have access to these sub-groups of trunks have a correspondingly smaller maximum number of trunks to test in order to find an idle one.

It will be seen from an examination of

the drawings that there is a trunk line extending from each selector group on the left to a non-numerical switch in each sub group on the right. In the first group of selector 5 trunks, the group in the upper left hand corner of Fig. 1, the first trunk leads to a non-numerical switch in the first sub group, or the sub group in the upper right hand corner of Fig. 1. The second trunk in this selector 10 group leads to a switch in the second sub group, the third trunk to a switch in the third sub group and so on. The trunks from the second group of selectors extend to switches in the several sub groups in the 15 same manner as those from the first selector group, except that a slip is introduced and trunk No. 1 in the second selector group leads to a switch in the third sub group, the second trunk to a switch in the fourth sub 20 group, and so on down to the last trunk in this group which leads to a switch in the second sub group. It will be observed that this same slip is carried out all along down the line. This slip distributes the traffic 25 evenly amongst the various sub groups.

This revision of the trunking arrangement, in decreasing the number of trunks in each sub group, not only decreases the time required for an idle trunk to be selected, but 30 when relay switches are used effects a great saving in equipment for the reason that the number of relays in such a switch is proportionate to the number of trunks to which the switch has access.

35 Referring now particularly to Fig. 3, the selector D shown therein is mechanically of the usual vertical and rotary type and accordingly has its bank contacts arranged in horizontal rows or levels. This switch is 40 operated according to the well known two-wire system of control. The circuits of this switch are shown complete and will be described fully hereinafter.

The non-numerical switch E³, which is 45 accessible to the selector D, does not have the usual mechanical trunk selecting movement but has instead a plurality of relays which operate one after the other to select an idle trunk. The circuits of this switch 50 also are shown complete and will be described fully hereinafter.

Each of the trunks to which the switch E³, together with the other switches in the same group, has access, is assumed to extend to a 55 repeater, such as the repeaters F, F', and F², Figure 4, and thence by way of a two conductor trunk line such as the trunk lines X, X', and X² to another office in the system. These repeaters F, F', and F² are all identical with each other and, with the exception 60 of an added relay, are identical with the two-wire repeaters that are now in common use.

65 The relay group RG shown in the lower part of Fig. 4 is used for the purpose of making all the trunks incoming to the group

busy as soon as all the outgoing trunks are taken for use, or rather, as soon as the last call arrives at the group. This operation will be explained more fully hereinafter.

Of the switches H, H', H², H³, and H⁴, Fig. 2, and of which only H, H' and H⁴ are shown in the detailed circuit drawing in Fig. 5, each is similar to the switch E³, Fig. 3, in that no mechanical step by step arrangement is employed to pick out an idle trunk line, but are different in that the trunks are pre-selected as will be explained more fully hereinafter.

The apparatus having been described more or less in general will now be described in connection with a detailed description of its operation. For this purpose, it will be assumed that a call comes through the exchange by way of the selector D, Fig. 3. The

selector D, it may be pointed out, is one of the selectors which has access to the second group of trunk lines on the left of Fig. 2, counting from the bottom. We shall assume further that when the call comes in none of the switches E-E⁴, inclusive, Fig. 2, are in use and consequently all of the trunks outgoing from that sub group are idle at this time.

When the call comes in as assumed, the selector D is seized at the bank contacts 2, 3, and 4, or their multiples, in which the trunk line comprising conductors 5, 6, and 7 terminates and line relay 10 is energized over the calling subscriber's loop in series with the impulse springs of the calling subscriber's calling device. Upon energizing, line relay 10

closes a circuit for release relay 11, including the resting contact of armature 30 of switching relay 14 and said armature, at armature 15. Release relay 11, upon energizing, opens a point in the circuit of release magnet 19 and closes a point in the circuit of slow acting relay 12 at armature 17, and at armature 16 places ground on release trunk conductor, 6, thereby establishing a holding circuit for the switching relay of the switch which seized the selector D.

The calling subscriber now manipulates his calling device in accordance with the next digit in the desired number, thereby producing a corresponding number of interruptions in the circuit of line relay 10. As soon as line relay 10 falls back in response to the first interruption produced in its circuit, it closes at armature 15 the circuit of the slow acting relay 12. The slow acting relay 12, upon energizing, prepares the circuit of stepping relay 13 at armature 22 and at armature 21 opens a point in the circuit of rotary magnet 23 and closes a point in the circuit of vertical magnet 20. Each time line relay 10 energizes at the end of an interruption produced in its circuit it opens the circuit of slow acting relay 12 and closes 120

the circuit of release relay 11 and vertical magnet 20 in multiple. Relays 11 and 12, 125

being slow acting, are both maintained energized throughout the series of interruptions. By the operation of the vertical magnet, which energizes each time its circuit is closed following an interruption in the circuit of the line relay 10, the switch shaft and wipers are raised step by step until the latter come to rest opposite the desired level of contacts, which will be assumed to be the level in which the trunk line comprising conductors 38-40, inclusive, terminates. As soon as the shaft of the switch is moved from its normal position the off-normal springs 26 close, thereby completing a circuit for stepping relay 13. Stepping relay 13, upon energizing, closes a locking circuit for itself at armature 25 in series with interrupter contacts 27, and at armature 24 prepares a circuit for rotary magnet 23. After the last interruption is produced in the circuit of line relay 10, armature 15 comes to rest against its working contact thus leaving the circuit of slow acting relay 12 open. Upon deenergizing, relay 12 opens the initial circuit of stepping relay 13 at armature 22 and at armature 21 opens the circuit of vertical magnet 20 and closes the circuit of rotary magnet 23. Rotary magnet 23, upon energizing, advances the wipers 32-34, inclusive into engagement with the first set of contacts in the level opposite which they are raised. Near the end of its stroke rotary magnet 23 separates the interrupter contacts 27, thereby opening the circuit of stepping relay 13. Stepping relay 13, upon deenergizing, opens another point in its circuit at armature 25 and at armature 24 opens the circuit of rotary magnet 23. Rotary magnet 23 now deenergizes and closes the interrupter contacts 27 again.

From this point, the operation depends upon whether the trunk line which terminates in the first set of contacts is busy or idle. If it is busy, test wiper 33 is in engagement with a grounded contact and stepping relay 13 energizes again over a circuit which includes wiper 33 and armature 29 and its resting contact. Upon energizing, stepping relay 13 closes the previously described locking circuit for itself at armature 25 and at armature 24 closes the circuit of rotary magnet 23. Rotary magnet 23, upon energizing, steps the wipers into engagement with the next set of contacts and again opens its interrupter contacts 27. This alternate operation of the rotary magnet and stepping relay continues until an idle trunk is found. In the present case, however, it has been assumed that the switches E-E', inclusive, Fig. 2, are idle and consequently the trunk line terminating in bank contacts 35-37, inclusive, which is the first set of contacts in the level, is idle, when the call is made as described. This being the case, there is no direct circuit closed for stepping relay 13 when wiper 33 arrives upon test contacts 36 and the switching relay 14 which has heretofore been short circuited immediately energizes over the following path: From ground by way of the working contact of armature 16 and the said armature, switching relay 14, interrupter contacts 27, off normal contacts 26, and stepping relay 13 to battery. Stepping relay 13, however, being wound with comparatively few turns is not able to energize over this circuit on account of the high resistance of switching relay 14. Switching relay 14, upon energizing, disconnects test wiper 33 from a point between its own winding and that of stepping relay 13 and connects it to the release trunk conductor 6 at armature 29; removes ground from the armature of line relay 10 at armature 30; and at armatures 28 and 31 disconnects the trunk conductors 5 and 7 from the upper and lower windings of line relay 10 and extends them by way of the working contacts of the said armature, line wipers 32 and 34, bank contacts 35 and 37, trunk conductors 38 and 40, armatures 58 and 61 and their resting contacts to the winding of line relay 50 of switch E' and ground, respectively. Line relay 50, upon energizing, places ground upon release trunk conductor 39 at armature 57, thereby establishing a holding circuit for the selector D and the switches back of it before the slow acting release relay 11 has had time to deenergize. It will be noted that as soon as ground is placed on release trunk conductor 39 by the pulling up of switching relay 14 of the switch D, the seized trunk is made busy immediately to the other switches having access to it. In this case, however, not only the seized trunk but also all the other trunks incoming to this group of switches is made busy through the common conductor 90 to which all the release trunk conductors are normally connected through the resting contacts of armature 60, 60', 63', etc. It is seen now that any other call which comes in at this stage will not take a trunk leading to the group in which the switch E' is located but will be diverted to some other group.

To continue with the operation of the switch E', line relay 50, upon energizing, in addition to placing ground on release trunk conductor 39 as described, closes at armature 56 the following circuit: from ground by way of armature 56 and its working contact, switching relay 51, armature 69 and its resting contact, armature 74 and its resting contact, and the lower winding of the relay 54 to battery. This circuit, it will be noted, includes relay 51 and the lower winding of the relay 54 in series. As a further result of the operation of the line relay 50, armature 55 is connected to a point between the winding of relay 51 and the lowe

winding of relay 54. Armature 55 is normally connected to ground through the resting contact of armature 59 and said armature, armature 63 and its resting contact, armature 67 and its resting contact, and armature 72 and its resting contact. Switching relay 51 is accordingly short circuited and prevented from energizing. Relay 54, however, energizes; closes a locking circuit for itself at armature 73; disconnects ground from the point between its lower winding and that of switching relay 51 at armature 72 and connects up release trunk conductor 77 instead; disconnects its own lower winding and connects up the lower winding of relay 53 at armature 74; and at armatures 71 and 75 connects up the upper and lower series of contacts and armatures to trunk conductors 76 and 78.

From this point the operation depends upon whether the trunk line comprising conductors 76-78, inclusive, is busy or idle. If it is busy release trunk conductor 77 is grounded and switching relay 51 is still short circuited. With this condition existing relay 53 energizes; closes a locking circuit for its own upper winding and opens the locking circuit of switching relay 54 at armature 68; connects the point between its own lower winding and the winding of switching relay 51 to release trunk conductor 80 at armature 67; disconnects its own lower winding and connects up the lower winding of relay 52 at armature 69; and at armatures 66 and 70 disconnects the trunk conductors 76 and 78 and connects up the trunk conductors 79 and 81. Relay 54 deenergizes now in response to the opening of its locking circuit but does not perform any particular function at this time. If the trunk line comprising conductors 79-81, inclusive, is busy at this time there is a ground potential on release trunk conductor 80 and relay 52 by action identical with that of relay 53 just described, transfers the connection to the trunk line comprising conductors 82-84, inclusive, and relay 53 deenergizes.

In the present case, however, we shall assume, as before stated, that the trunk line comprising conductors 76-78, inclusive, is idle at this time and consequently there is no ground potential on release trunk conductor 77, and as soon as relay 54 has energized and transferred the circuits in the manner described, switching relay 51 energizes in series with the lower winding of relay 53. Relay 53, however, does not energize in series with the switching relay 51 on account of the high resistance of the said switching relay 51. Switching relay 51, upon energizing, disconnects release trunk conductor 77 from the point between its own winding and the lower winding of relay 53 at armature 59 and connects it to ground through the working contact of armature 56 and said armature, thus causing the seized trunk to test busy immediately to the other switches having access to it; disconnects release trunk conductor 39 from the common conductor 90 at armature 60 and connects it by way of the previously traced series of armatures and contacts to release trunk conductor 77; and at armatures 58 and 61 disconnects trunk conductors 38 and 40 from the winding of relay 50 and ground, respectively, and extends them by way of armatures 62 and 65 and their resting contacts, armatures 66 and 70 and their resting contacts, armatures 71 and 75 and their working contacts, trunk conductors 76 and 78, and the normally closed contacts controlled by armatures 110 and 111 to the upper and lower windings of the double wound line relay 102 of repeater F. Line relay 102 now energizes over the calling subscriber's loop and at armature 113 opens a point in the circuit of slow acting relay 103 and closes a circuit for relays 104 and 105 in multiple. Relay 105, upon energizing, among other things which will be pointed out more fully hereinafter, disconnects relay 104 from the working contact of armature 113 and substitutes a circuit through armature 120 and its working contact. Relay 104, upon energizing, places ground upon release trunk conductor 77 at armature 117. This occurs before the slow acting line relay of the switch E³ has had time to deenergize and maintains a holding circuit for the switch E³ and other switches behind it.

Returning now to the repeater F, as a further result of the energization of relay 104, it closes at armature 119 a circuit for the lower winding of electropolarized relay 106. This winding alone, however, consisting of a small number of turns of a relatively high resistance, is not able to effectively energize the relay. As a still further result of the energization of relay 104 it prepares a circuit for slow acting relay 103 at armature 118, and at armature 116 completes a bridge across the conductors of the trunk line X as follows: From the lower conductor of trunk line X by way of the working contact of armature 114 and said armature, right hand winding of impedance 107, normally closed contacts controlled by armature 112, upper winding of electropolarized relay 106, resting contact of armature 115 and said armature, and the working contact of armature 116 and said armature to the upper conductor of trunk line X. In response to the closure of this bridge, the line relay of the automatic switch on the other end of the trunk line X is energized and the switch is prepared for operation in the usual manner. Current is now flowing through both the upper and lower windings of electropolarized relay 106 but the said relay is not energized at this time because the

current flowing in either winding is opposite in direction to that flowing in the other.

The calling subscriber now manipulates his calling device in accordance with the next 5 digit in the desired number, thereby producing a corresponding number of interruptions in the circuit of line relay 102. Each time line relay 102 deenergizes in response to one of these interruptions it opens the circuit 10 of the line relay of the automatic switch on the distant end of the trunk line at armature 114, thereby causing the said switch to operate in the usual manner. Slow acting relay 103 is maintained energized through- 15 out the series of interruptions over a circuit which includes armature 113 and its resting contact and armature 118 and its working contact. Upon energizing, slow acting relay 103 completes the bridge across the conductors of the trunk line X by a more direct 20 path, which excludes the right hand winding of impedance 107 and the upper winding of electropolarized relay 106 at armature 115 and its working contact. This is the usual 25 expedient made use of in order to obtain first class switch control. At the end of the series of interruptions, line relay 102 comes to rest in an energized condition and slow 30 acting relay 103, upon deenergizing, restores the bridge across the conductors of the trunk line X to its previously traced path.

The calling subscriber may now go ahead and dial the remaining digits of the desired number, the repeater F functioning for each 35 digit in the manner described. When the connection is finally completed and the called subscriber has been signalled and has responded by removing his receiver, the current flow in the trunk line X and consequently in the bridge across the conductors 40 of the said line in the repeater F is reversed by the final switch in the distant exchange. When this occurs, the two windings of electropolarized relay 106 which heretofore 45 have opposed each other now assist each other in energizing the relay. Upon energizing, relay 106 places a shunt around armature 115 and its resting contact at armature 124; places a shunt around armature 50 114 and its working contact at armature 125; and at armature 126 closes the circuit of reversing relay 101. Upon energizing, reversing relay 101 shifts the bridge across the 55 trunk line X so as to include both windings of impedance 107 at armature 112, and at armatures 110 and 111 reverses the incoming trunk conductors 76 and 78 as regards their connection with the upper and lower windings of line relay 102. This reversal of current flow is used in some cases to operate 60 meters, coin boxes and the like but does not have anything in particular to do with the present invention, the circuits being shown in this manner because of the fact that it is more or less a standard arrangement. The

calling and called subscribers may now converse with each other as desired, the talking circuits that are shown being outlined by heavy conductors.

When the conversation is completed the 70 calling and called subscribers replace their receivers. When the receiver is replaced at the called substation the current flow in the conductors of the trunk line X is reversed back to normal whereupon electropolarized 75 relay 106 retracts its armatures and upon so doing removes the shunt from around armature 115 and its resting contact at armature 124; removes the shunt from around armature 114 and its working contact at armature 125; and at armature 126 opens the circuit of reversing relay 101. Reversing relay 101, upon deenergizing, reverses the current flow in the calling subscriber's loop back to normal. This operation, however, does 80 not perform any useful function in the 85 present case.

When the receiver is replaced at the calling substation the circuit of line relay 102 of repeater F is opened and the said relay, 90 upon deenergizing, opens the bridge across the conductors of the trunk line X at armature 114, whereupon, the automatic switches in the distant exchange restore themselves to normal position in the usual 95 manner. As a further result of the deenergization of line relay 102, it opens the circuit of slow acting release relay 105 and closes the circuit of slow acting relay 103 at armature 115. Release relay 105, upon deenergizing, opens the circuit of relay 104 at armature 120. Relay 104, upon deenergizing, opens the circuit of slow acting relay 103 at armature 118 and at armature 117 removes ground from release trunk conductor 77. When ground is removed from release trunk conductor 77, relay 54 and switching relay 51 of the switch E³, and switching relay 14 of the selector D, together with the switching relays of the various other switches which were engaged in the connection before the selector D was reached, de-energize. The deenergization of the two relays mentioned in the switch E³ restores that switch to normal condition and connects up release trunk conductor 39 to common conductor 90 at armature 60. 100 105 110 115 120 125 130

In the selector D, switching relay 14, upon deenergizing, completes a circuit for release magnet 19 as follows; from ground by way of resting contact of armature 30 and said armature, armature 15 and its resting contact, armature 17 and its resting contact, off-normal contacts 18, and release magnet 19 to battery. By the operation of the release magnet, the shaft and wipers of the selector D are restored to normal position in the usual manner, the circuit of release magnet 19 being opened at off-normal contacts 18 by the switch shaft when it reaches normal 125 130

position. The other switches engaged in the connection before the selector D was reached are restored to normal position in the usual manner. The entire connection is now released and the apparatus is now ready for another call.

Referring now again to Figs. 3 and 4, the function of the relay group RG, Figure 4, together with its associated equipment will 10 now be explained in detail. We shall assume that the group of trunks, to which the switch E³ and others has access, is idle and that a call comes in over one of the switches, the switch E³ for example. As soon as the trunk 15 line comprising conductors 38, 39 and 40 leading to the switch E³ is seized by a selector such as the selector D, a ground potential is thrown upon release trunk conductor 39 by the selector in order to make the seized 20 trunk busy immediately. This ground potential, as hereinbefore pointed out, extends by way of the common conductor 90 to the release trunks of all the switches, in that group. This ground potential extends also 25 by way of conductor 90 to relay 130 of the relay group RG, Fig. 4. Relay 130, upon energizing, connects the common conductor 90 with conductor 142 at armature 134. This operation, however, does not perform any 30 particular function at this time. As soon as the various relays of the switch E³ have had time to function, release trunk conductor 39 is disconnected from common conductor 90 at armature 60 of switching relay 51, 35 whereupon relay 130 of relay group RG de-energizes and disconnects the common conductor 90 from conductor 142. As a further result of the energization of switching relay 51 of the switch E³, the trunk line ex- 40 tending to the repeater F is seized and the repeater is made ready for operation in a manner hereinbefore explained. As soon as relay 105 of repeater F, is energized, the first one of a chain of contacts in the circuit 45 of relay 132 of relay group RG is closed at armature 121, and at armature 122 the resist- 50 ance 123 is disconnected from conductor 139 and ground is placed on the latter, thereby closing a circuit for relay 131 of relay group 55 RG by way of armatures 138 and 137. A circuit is closed at this time for relay 133 of relay group RG as follows: from ground by way of conductor 139, armatures 122' and 122² in multiple and their resting contacts, 60 resistances 123' and 123², conductor 141, and relay 133 to battery. Relays 131 and 133 en- 65 ergize simultaneously and the latter, upon energizing, opens the circuit of the former at armature 138, whereupon, the said relay 131 deenergizes. It is seen now that with 70 one of the repeaters of the group comprising repeaters F, F' and F² busy, ground is placed on conductor 139 to close the circuit of relay 131 but relay 133 is energized and 75 has the circuit of the former relay open.

We shall assume that another call comes in and that one of the non-numerical switches in the group in which the switch E³ is located seizes one of the remaining repeaters, the repeater F² for example. As soon as the non-numerical switch is seized, ground is placed on the common conductor 90 in a manner described before but does not produce any result in the relay group RG other than merely operating relay 130. 75 As soon as the non-numerical switch has had time to function and seize the repeater F² ground is removed from the common conductor 90 and relay 130 deenergizes. Relay 105² of the repeater F², upon energizing, 80 closes another point in the circuit of relay 132 at armature 121², removes the resistance 123² from the circuit of relay 133 and places a multiple ground on conductor 139 at armature 122². Relay 133, which is marginally adjusted, deenergizes at this time since its circuit is closed through only the resistance 123' and completes the circuit of relay 131 at armature 138. Relay 131, upon energizing, places ground on conductor 142 85 at armature 135. This is done in preparation so as to place ground on the common conductor 90 at relay 130 as soon as the sole remaining outlet from this group is taken 90 for use. 95

Assuming now that another non-numerical switch in this group is seized, ground is thrown upon common conductor 90 in the usual manner, whereupon relay 130 of the relay group RG energizes and connects the common conductor 90 with conductor 142 which is grounded at armature 135 of relay 131. As soon as the non-numerical switch has functioned, its release trunk is disconnected from the common conductor 90 and the repeater F' is seized in the usual manner. All the outlets from this group of switches are in use and if another call were permitted to come into this group at this time it would be lost for the lack of an outlet. No 100 call can come into this group at this time, however, for the reason that the common conductor 90 is maintained grounded by relay 130 of relay group RG and, consequently, the calls are shifted to such other groups of non-numerical switches as have idle trunks leading out from them. As soon as relay 105' of the repeater F' has energized in response to seizure of this repeater, it 105 completely opens the circuit of relay 133 at armature 122'. This, however, does not produce any effect in the relay group RG as relay 133 is already deenergized. As a further result of the deenergization of relay 105' it completes the circuit of relay 132 at armature 121'. Relay 132, upon energizing, 110 opens the circuit of relay 131 at armature 137 and at armature 136 places a multiple ground on conductor 142 and consequently 115 on common conductor 90. Relay 131, upon 120 energizing, places ground on conductor 142 at armature 135. This is done in preparation so as to place ground on the common conductor 90 at relay 130 as soon as the sole remaining outlet from this group is taken 125 for use. 130

deenergizing, disconnects conductor 142 from ground at armature 135 but the said conductor is still grounded at armature 136.

We shall assume for the sake of illustration that the subscriber who is using the switch E^3 and the repeater F finishes his conversation and replaces his receiver. With the assumption as noted, the connection is released in a manner hereinbefore described and release trunk conductor 39 of the switch E^3 is connected to the common conductor 90 again. As soon as relay 105 of repeater F deenergizes, a circuit is closed for relay 133 of the relay group RG in series with resistance 123 but owing to its marginal adjustment, relay 133 is not energized at this time. As a further result of the deenergization of relay 105, it opens the circuit of relay 132 at armature 121. Relay 132, upon deenergizing, removes ground from conductor 142 and consequently from the common conductor 90 at armature 136 and at armature 137 closes the circuit of relay 131. Relays 130 and 131 are so adjusted that the armature of relay 130 falls back slightly quicker than the armature of relay 131 is attracted and consequently relay 130 deenergizes at this time and disconnects the common conductor 90 from conductor 142 at armature 134 before relay 131 has had time to energize. The circuit conditions of the relay group RG are now the same as they were just before the repeater F' was seized, that is, conductor 142 is grounded and the circuits are in readiness for placing ground on the common conductor 90 as soon as the last outlet from this group is taken for use.

If we assume now that one of the repeaters F' or F^2 , the repeater F^2 for example becomes idle, thus giving more than one available outlet from this group, before another call comes in to this group, the circuit of relay 131 is opened and ground is removed from conductor 142 as will now be pointed out. Relay 105², upon deenergizing, opens at armature 121² still another point in the circuit of relay 132 at armature 121², and at armature 122² places resistance 123² in multiple with resistance 123 whereupon, the marginally adjusted relay 133 energizes and opens the circuit of relay 131 at armature 138. Relay 131 now deenergizes and removes ground from conductor 142 at armature 135.

It will be seen now that each time a switch in this group is taken for use the common conductor 90, which has the release trunk conductors of all the idle inlets connected with it, is connected with the conductor 142 of the relay group RG, and if there is only one remaining outlet from the group there is a ground potential on conductor 142, and relay 130 will become locked. Consequently, when the switch cuts through and the last

outlet is taken for use, conductor 90 is not cleared but remains connected with the grounded conductor 142, thereby busying all the inlets into this group. It is seen further that the seizure of the last outlet 70 is accompanied by a transfer of the ground connection on conductor 142 so as to permit the unlocking of relay 130 as soon as an outlet again becomes available. The advantage of the arrangement described lies in 75 the fact that when there is only one available outlet from a group, the busying of the inlets to such group will occur simultaneously with the seizure of the next switch, and all possibility of a call being extended to a secondary switch having no idle outlets is eliminated. 80

It is to be understood that this same arrangement of making incoming trunks busy may be used in a situation in which there are more outlets than are shown in the present drawings. When other outlets are added, the repeaters associated therewith, will have their "make busy" contacts connected in the same manner as those of the intermediate 90 repeater F' and these other repeaters may be inserted between either the repeaters F and F' or the repeaters F' and F^2 .

It will be convenient to explain at this time that the switch E^3 , Figure 3, may be given access to as many outgoing trunks as desired by adding more trunk selecting relays and that, without adding any relays or other equipment, an additional trunk can be connected to the resting contacts of armatures 71, 72, and 75 of relay 54. In that case, of course, the ground which is shown connected to the resting contacts of armature 72 is removed. With this extra trunk, if there is no ground on the resting contact of 105 armature 72 of relay 54 when the switch E^3 is seized, it being assumed of course that the trunk in question is idle, then the energization of line relay 50 is followed immediately by the energization of switching 110 relay 51, which switches the connection through to the normally connected trunk line. In case still more trunks are desired they can be had, as before stated, by adding one relay per trunk together with its associated armatures and contacts. Each of these added relays may have a spring assembly identical with that of relay 53 and may be inserted either between relays 52 and 53 or between relays 53 and 54. This increase 115 in trunk capacity may be carried out as far as is desired, or until the cost of the switch equals or surpasses the cost of a switch having a mechanical step by step trunk selecting movement. 120

It will be stated at this point that switches similar to the switch E^3 , Fig. 3, are assumed to be used in the entire layout shown in Figs. 1 and 2 with the exception of the group comprising switches $H-H^4$, in 130

clusive, which are of a different type. This assumption however is made solely for convenience and to avoid the necessity of duplicating the layout, it being understood that in practice switches of one type or the other will ordinarily be used exclusively in any given situation.

Referring now particularly to Fig. 5, which is a circuit drawing of the switches H, H', and H⁴ of the group comprising switches H-H⁴, inclusive, Fig. 2, the switches H² and H³ are omitted, their circuits being identical with the circuits of switch H'. For the purpose of illustration it will be assumed that all the switches in the group comprising switches H-H⁴, inclusive are idle at this time and that the switch H is seized from one of the selectors which has access to the trunk line comprising conductors 201-203, inclusive. With the assumption as noted, a ground potential is placed upon the release trunk conductor 202 immediately by the selector so as to make the seized trunk busy to the other switches having access to it. This ground potential extends by way of armature 216 and its resting contact, armature 223 and its resting contact, and armature 225 and its resting contact, to common conductor 292 to which all the release trunk conductors of the incoming trunks are normally connected. This makes all the incoming trunks associated with this group temporarily busy and prevents two calls from being received in this group simultaneously, the other calls being shifted to other groups. This ground potential extends also through armature 218 and its resting contact, armature 224 and its resting contact, and armature 226 and its resting contact to conductor 294 to which the trunk selecting relays 210, 211, and 212 are normally connected. Similarly this ground potential extends by way of a similar series of armatures and contacts in the switch H' to conductor 295 to which all the relays of this switch are normally connected. The same thing is true for each of the other switches in the group. The other terminal of the relays 212, 246, and 249 are normally connected to common conductor 289, and relay 211 together with the similarly located relays in the other switches is connected to the common conductor 287. Neither common conductor 287 nor common conductor 289 has a battery potential on it at this time and consequently none of the relays mentioned energize. Common conductor 285, to which relay 210 and the similarly located relays in the other switches are normally connected, is connected to battery at this time through the resting contact of armature 221 and said armature, resting contact of armature 232 and said armature, similar contacts and armatures on the switches H² and H³ and the resting contact of armature

252 and said armature. That being the case, the first relay in each switch in this group starts to energize as soon as ground is placed upon release trunk conductor 202 as previously described. Relay 210, upon energizing, disconnects release trunk conductor 202 from common conductor 292 at armature 216, thereby making the remaining switches in this group accessible and allowing all the other relays that started to pull up, responsive to the placing of a ground potential on conductor 292, to fall back. As a further result of the energization of relay 210 it locks itself to release trunk conductor 202 and disconnects itself from conductor 294 at armature 219; locks itself to battery and disconnects itself from common conductor 285 at armature 220; places ground on conductor 290 at armature 217; disconnects release trunk conductor 202 from conductor 294 at armature 218; removes battery from conductor 285 and places it upon conductor 286 at armature 221; connects release trunk conductor 202 with release trunk conductor 276 of the seized trunk at armature 216; and at armatures 215 and 222 connects conductors 201 and 203 with conductors 275 and 277 of the seized trunk. The line and release relays of the automatic repeater to which the trunk line comprising conductors 275-277, inclusive, extends, immediately energize and prepare the switch for operation in the usual manner, and the latter, upon energizing, places ground upon release trunk conductor 276 thereby establishing the usual holding circuit.

The calling subscriber may now go ahead and dial the remaining digit of the desired number in the usual manner.

If we assume that another call comes in at this time and that the switch H' is the one seized, a ground potential is sent forward over the release trunk conductor 205, through the series of contacts shown, to common conductor 292 and thence to the release conductors of all the idle switches in this group. The battery potential which was placed on conductor 286 by the energization of relay 210 as explained now extends by way of armature 255 and its resting contact, similar armatures and contacts in switches H³ and H², armature 239 and its resting contact, and armature 264 and its resting contact to conductor 287. Accordingly relay 245 and the corresponding relays in the switches H²-H⁴, inclusive start to energize as soon as the ground potential is thrown upon release trunk conductor 205. There is no battery potential on common conductors 285 and 289, however, and consequently the associated relays do not energize. Relay 245, upon energizing, disconnects release trunk conductor 205 from common conductor 292 at armature 234 whereupon, all the other relays which started to energize at this time

deenergize and the remaining idle switches are made accessible again. As a further result of the energization of relay 245 it locks itself to release trunk conductor 205 and disconnects itself from conductor 295 at armature 237; locks itself to battery and disconnects itself from conductor 287 at armature 238; extends the ground potential which is on conductor 290 to conductor 291 at armature 235; disconnects release trunk conductor 205 from conductor 295 at armature 236; disconnects battery from conductor 287 and extends it to conductor 288 at armature 239; connects release trunk conductor 205 with release trunk conductor 279 of the seized trunk at armature 234; and at armatures 233 and 240 connects conductors 204 and 206 with trunk conductors 278 and 280 of the seized trunk. The line and release relays of the switch to which the trunk line comprising conductors 278-280, inclusive, extends now energize in the usual manner and the latter places ground on release trunk conductor 279, thereby establishing the usual holding circuit.

Assuming now that another call comes in to this group and that it takes the switch H^4 , the ground potential which is placed upon release trunk conductor 208 is extended forward to common conductor 292 and thence to the release trunk conductors of the switches in this group which are idle at this time. The battery potential which was placed upon conductor 288 by the energization of relay 245 of the switch H' extends by way of armature 262 and its resting contact, corresponding armatures and contacts in the switches H^3 and H^2 , armature 243 and its resting contact, and armature 227 and its resting contact to conductor 289. As a result relay 249 and the corresponding relays in switches H^3 and H^2 commence to energize as soon as the ground potential is placed upon release trunk conductor 208. In this case there is no battery potential upon conductors 285 and 287 and consequently neither relay 247 nor 248 of the switch H^4 nor the corresponding relays in the other switches in this group which are idle at this time can energize. Relay 249, upon energizing, removes the ground potential from common conductor 292 at armature 257, whereupon, the corresponding relays in the switches H^2 and H^3 Fig. 2, fall back. As a further result of the energization of relay 249 it locks itself to release trunk conductor 208 and disconnects itself from conductor 295, at armature 260; locks itself to battery and disconnects itself from conductor 289 at armature 261; extends the ground potential which is on conductor 291 to common conductor 292 at armature 258; disconnects release trunk conductor 208 from conductor 295 at armature 259; disconnects battery from conductor 289 at armature 262, connects release trunk con-

ductor 208 with release trunk conductor 282 of the seized trunk at armature 257; and at armatures 256 and 263 connects up conductors 207 and 209 with conductors 281 and 283, respectively, of the trunk line comprising conductors 281-283, inclusive. The line and release relays of the switch to which the seized trunk extends now energize in the usual manner and the latter places ground on release trunk conductor 282 thereby establishing the usual holding circuit.

All the outlets from this sub group of switches are now in use and if a call were permitted to come into this group at this time it would be lost for the lack of an outlet. Calls are prevented from coming into this group at this time by the ground potential which is extended forward by way of conductors 290 and 291 to common conductor 292 to which the release trunk conductors of the idle switches H^2 and H^3 are connected.

In case the switch H becomes idle the battery potential will be replaced upon common conductor 285 thus making the first outgoing trunk available, and at the same time ground is removed from conductor 290 and consequently from common conductor 292 thus making the idle switches in this group available again. On the other hand if we consider that the switch H' becomes idle while the switch H is yet busy the battery potential will be replaced on common conductor 287 instead of on common conductor 285 thus making the second trunk line in the group available.

It will be noted that these switches $H-H^4$, inclusive, always take the first trunk when it is idle, taking the second trunk only when the first trunk is busy and the third only when the second trunk is busy. This, while not objectionable perhaps from a theoretic standpoint, is sometimes undesirable from a practical standpoint owing to the fact that all the trunk lines are not used alike and the switches associated with the trunks which are used the most are subjected to the most wear and may have to be replaced often while the others are practically unused except during the peak of the load which occurs periodically. This seeming difficulty can be obviated, if desired, in a manner which will now be pointed out. Working contacts may be placed on armatures 227, 243, corresponding armatures on switches H^2 and H^3 , and armature 262 to which a common conductor may be wired. This common conductor may be extended to armature 252 of relay 247. This makes the battery transfer circuit a complete loop. With this loop wired as described the battery connection may be removed from armature 252 and placed on either armature 255 or armature 262, thus making the associated trunk line first choice. Any suitable method or means for shifting the battery potential

from one armature to the other may be employed, for example, it may be shifted periodically by an attendant by means of the switch S, or it may be shifted upon the extension of each call by a master switch arrangement.

It is to be understood that in case more outgoing trunks are desired they may be had by adding one relay to each switch together with the proper contacts and associated conductors. These relays may be inserted between the row comprising relays 211, 245, etc. and the row comprising relays 212, 246, etc., or between the first named row and the row comprising relays 210, 244, etc. It is to be understood also that more switches may be added in a group and that each added switch will be similar to the switch H' and may be inserted anywhere along the line between the switches H and H⁴.

While the explanation might be still further amplified it is thought that the foregoing is sufficient to enable the invention to be thoroughly understood by those who are skilled in the art and to whom this specification is directed.

The various features of the invention having been thus described and ascertained will now be pointed out in the appended claims.

What is claimed is:

1. In a telephone system, a trunking section comprising incoming and outgoing trunks, each trunk having two line conductors and a release trunk conductor, a switching device for each incoming trunk comprising a relay for each outgoing trunk, and a circuit completed over the release trunk conductor of an incoming trunk when such trunk is taken for use for energizing the particular relay of the associated switching device which corresponds to an idle outgoing trunk.

2. In a telephone system, a trunking section comprising incoming and outgoing trunks, each trunk having two line conductors and a release trunk conductor, a switching device for each incoming trunk comprising a relay for each outgoing trunk, a circuit completed over the release trunk conductor of an incoming trunk when such trunk is taken for use for energizing the particular relay of the associated switching device which corresponds to an idle trunk, said circuit including parallel branches through the corresponding relays in all the other idle switching devices, and contacts controlled by the energized relay for opening said parallel branches.

3. In a telephone system, a trunking section comprising incoming and outgoing trunks, each trunk having two line conductors and a release trunk conductor, means for connecting incoming trunk lines with outgoing trunk lines, said means comprising

ing as many relays as there are incoming trunk lines multiplied by the number of outgoing trunk lines, means for energizing said relays over the release trunk conductors of incoming trunk lines, and means for maintaining said relays energized over the release trunk conductors of outgoing trunk lines.

4. In a telephone system, incoming and outgoing trunk lines each having two line conductors and a release trunk conductor, a relay normally connected to the release trunk conductor of the incoming trunk line, means for temporarily grounding the release trunk conductor of the incoming trunk line when it is taken for use, the relay being energized to connect the two trunk lines, and means for grounding the release trunk conductor of the outgoing trunk to maintain said relay energized.

5. In a telephone system, incoming trunk lines, outgoing trunk lines extending at right angles thereto, relays at the points of intersection whereby any incoming trunk may be connected with any outgoing trunk, and local series circuits extending through rows of relays parallel to the direction of the incoming and outgoing trunks, respectively, for controlling the selection of an idle outgoing trunk.

6. In a telephone system, a selector switch having directive primary and automatic secondary movements, primary and secondary motor magnets, a line relay, a switching relay for disconnecting the line relay, and circuits for said magnets controlled directly and jointly by said relays.

7. In a telephone system, a selector switch having directive primary and automatic secondary movements, primary and secondary motor magnets, a line relay for the switch having a pair of contacts, a switching relay for disconnecting the line relay and also having a pair of contacts, and a circuit for both said magnets including both pairs of contacts in series.

8. In a telephone system, a selector switch having directive primary and automatic secondary movements, primary and secondary motor magnets, a line relay having a pair of contacts closed when the relay is energized, a normally open circuit for the primary magnet passing through said contacts, means for momentarily deenergizing the line relay a plurality of times, a slow acting relay maintained energized by the line relay during a series of deenergizations thereof, and contacts on said slow acting relay for closing the said primary magnet circuit.

9. In a telephone system, a selector switch having directive primary and automatic secondary movements, primary and secondary motor magnets, a line relay having a pair of contacts closed when the relay is energized, a circuit for the primary magnet in-

- cluding said contacts and a second pair of normally open contacts, means for causing a series of deenergizations of the line relay, and a slow acting relay maintained energized by the line relay during said series of deenergizations to close said second pair of contacts at the beginning of the series and to open the same at the end of the series. 5
10. In a telephone system, a selector switch having directive primary and automatic secondary movements, primary and secondary motor magnets, a line relay having a pair of contacts closed when the relay is energized, a normally open circuit for the primary magnet passing through said contacts, means for momentarily deenergizing the line relay a plurality of times, a slow acting relay maintained energized by the line relay during a series of deenergizations thereof, contacts on said slow acting relay for closing the said primary magnet circuit when the relay is energized, and a circuit for said secondary magnet closed by said slow acting relay when the relay is deenergized. 15
20. 11. In a telephone system, a selector switch having directive primary and automatic secondary movements, primary and secondary motor magnets, a line relay having a pair of contacts closed when the relay is energized, a circuit for the primary magnet including said contacts and a second pair of normally open contacts, means for causing a series of deenergizations of the line relay, a slow acting relay maintained energized by the line relay during said series of deenergizations to close said second pair of contacts at the beginning of the series and to open the same at the end of the series and a circuit for said secondary magnet closed by said slow acting relay when the same is deenergized. 25
30. 12. In a telephone system, a selector switch having primary and secondary movements, primary and secondary motor magnets, means for operating the primary magnet of said switch to cause the primary movement thereof, a circuit for the secondary magnet, a low resistance stepping relay energized at the beginning of the primary movement to close a point in said circuit, means for completing said circuit at the end of the primary movement, a switching relay, a test circuit for intermittently actuating said stepping relay to operate the secondary magnet by means 35
40. 55. of the said circuit thereof, said test circuit excluding said switching relay, a circuit for energizing the switching relay in series with the said stepping relay at the end of the secondary movement, and contacts on said switching relay for opening the circuit of the said secondary magnet to prevent the operation thereof in case the said stepping relay is energized when connected in series with the switching relay. 60
65. 13. In a telephone system, a trunking section comprising incoming and outgoing trunks, each trunk having two line conductors and a release trunk conductor, a switching device for each incoming trunk comprising a relay for each outgoing trunk, means for taking said trunk section for use, said means including a switching relay, a circuit completed over the release trunk conductor of an incoming trunk when said trunking section is taken for use for energizing the particular relay of the associated switching device which corresponds to an idle outgoing trunk, and means establishing a holding circuit for said last mentioned relay and the winding of the switching relay connected in parallel. 70
75. 14. In a telephone system, a trunk selecting switch having directive primary and automatic secondary movements, a plurality of trunking sections accessible thereto, each trunking section having a plurality of outgoing trunks, a switching device for each of said trunking sections comprising a relay for each outgoing trunk, and a circuit completed when the selecting switch selects a trunking section for energizing the particular relay of the associated switching device which corresponds to an idle outgoing trunk. 80
85. 15. In a telephone system, a selector switch having directive primary and automatic secondary movements, primary and secondary motor magnets, a line relay, a switching relay for disconnecting the line relay, circuits for said magnets controlled jointly by said relays, a trunking section accessible to said switch, said trunking section having a plurality of outgoing trunks, a relay for each outgoing trunk, and circuit connections including the winding of one of said last mentioned relays associated with an idle trunk and the winding of the switching relay, established when the selector selects the trunk section. 90
95. 16. In a telephone trunking section, incoming and outgoing trunk lines each having two line conductors and a release trunk conductor, a relay connecting the two trunks when it is operated, a circuit established over the release trunk conductor of the incoming trunk line when that trunk line is taken for use for temporarily operating the relay, and a circuit established over the release trunk conductor of the outgoing trunk line for maintaining said relay operated. 105
110. 17. In a telephone trunking section, a plurality of incoming trunks, an outgoing trunk, a relay individual to each incoming trunk for connecting it to the outgoing trunk, each incoming trunk including a release conductor, means for energizing all the relays over any one of said last mentioned conductors, and means effective upon the initial operation of the relay in the trunk containing the conductor over which the relays are en- 115
120. 125. 130.

ergized to open the circuit for the other relays.

18. In a telephone trunking section, a plurality of incoming trunks, an outgoing trunk, a relay individual to each incoming trunk for connecting it to the outgoing trunk, each incoming trunk including a release conductor, means for energizing all the relays over any one of the release conductors, means controlled by each relay for preventing its full operation over the conductor of any trunk other than the trunk to which it is individual, and means effective upon the initial operation of the relay in the trunk containing the release conductor over which the relays are energized to open the circuit of the other relays.

19. In a telephone trunking section, a plurality of outgoing trunks, a greater number of incoming trunks, a plurality of relays for connecting any incoming trunk with any idle outgoing trunk, means dependent upon which outgoing trunks are busy to predetermine the next outgoing trunk to be taken for use, and switching means for changing the sequence with which the outgoing trunks are taken into use.

20. In a telephone trunking section, a plurality of outgoing trunks, a greater number of incoming trunks, a plurality of relays individual to each incoming trunk each for connecting the trunks to a different outgoing trunk, means effective when any incoming trunk is taken into use for operating the relay of that incoming trunk which corresponds to a preselected idle outgoing trunk to connect the two, and means controlled by said relay to preselect a different idle outgoing trunk to be next taken into use, the selection of the outgoing trunk being the same regardless of which incoming trunks are taken into use.

21. In a telephone system, a directively operated switch having primary and secondary movements, said switch including a line relay having front and back contacts, a slow to release relay operated over a circuit including a front contact on the line relay, a second slow to release relay operated over a circuit including a back contact on the line relay and a front contact on the first slow to release relay in series, and a motor magnet for giving the switch its primary movement, the circuit for the motor magnet being controlled over a front contact on the line relay and a front contact on the second slow to release relay in series.

22. In a telephone system, a selector

switch having directive primary and automatic secondary movements, primary and secondary motor magnets, a line relay having front and back contacts, a slow to release relay operated over a circuit including a front contact on the line relay, a second slow to release relay operated over a circuit including a back contact on the line relay and a front contact on the first mentioned slow to release relay, the circuit for the primary motor magnet being controlled over a front contact on the second mentioned slow acting relay and a front contact on the line relay, and the circuit for the secondary motor magnet being controlled over a back contact on the second mentioned slow acting relay and a front contact on the line relay. 75

23. In a telephone system, a selector switch having directive primary and automatic secondary movements, primary and secondary motor magnets, a line relay having front and back contacts, a slow to release relay operated over a circuit including a front contact on the line relay, a second slow to release relay operated over a circuit including a back contact on the line relay and a front contact on the first mentioned slow to release relay, the circuit for the primary motor magnet being controlled over a front contact on the second mentioned slow acting relay and a front contact on the line relay, and the circuit for the secondary motor magnet being controlled over a back contact on the second mentioned slow acting relay and a front contact on the line relay, and means effective until the second slow to release relay operates to prevent the movement of the secondary magnet. 90

24. In a telephone system, a selector switch having directive primary and automatic secondary movements, primary and secondary motor magnets, a switching relay 100 having a back contact, a line relay having both back and front contacts, the circuit for both of said magnets including the back contact on the switching relay and a front contact on the line relay, and a slow acting relay having front and back contacts, the circuit for the primary magnet extending through a front contact on said slow acting relay and the circuit for the secondary magnet extending through a back contact on said slow acting relay, and means for maintaining the slow acting relay operated only during the time that impulses are being transmitted to the line relay. 110

RODNEY G. RICHARDSON.
